UNITED STATES PATENT OFFICE.

SAMUEL HENRY ADAMS AND COLIN HENRY ADAMS, OF FULFORD, ENGLAND.

FLUID OR AIR DIRECT-PRESSURE LIFTING AND FORCING APPARATUS FOR SOLIDS AND SEMISOLIDS.

1,347,358.

Specification of Letters Patent.

Patented July 20, 1920.

Application filed February 28, 1919. Serial No. 279,830.

To all whom it may concern:

Be it known that we, SAMUEL HENRY ADAMS and COLIN HENRY ADAMS, both subjects of the King of Great Britain, and residents of Fulford, York, England, have invented new and useful Improvements in Fluid or Air Direct-Pressure Lifting and Forcing Apparatus for Solids and Semisolids, of which the following is a specification.

Our invention relates to apparatus for the raising and discharge of solids and semisolids such as coke breeze, coal clinker, sand, heavy oils and pulp and other such material which would owing to their nature of necessity jam and block up an ordinary ejector of the direct air pressure displacement type.

According to our invention, in order to prevent such jamming and blocking of the ejector we make the receptacle with a closed rounded bottom and we perforate the mass of material with pipes or tubes or other fittings which are suitably held within the receptacle and through these a given proportion of the pressure-fluid, *e. g.* compressed air or pressure water or steam, or of a mixture of such fluids, will pass, exerting its pressure either for lifting or forcing the material from beneath as well as from above and in this way loosening and breaking up the mass to such an extent that it will enter into the lower open end of a discharge pipe extending downwardly into the receptacle and be driven up to the height required. We use suitable connections through which the pressure fluid is discharged in jets or in a stream into any desired part of our ejector or its fittings, as for instance into the body of the mass of material, and into the intake mouth of the discharge pipe and into the inlet and outlet valves and other fittings, provided always that these jets are so placed that they expedite the entry of the material into the ejector body and the discharge of the material from it, and in this way we make it possible to handle solid and semisolid material, whether in a dry or wet state, by means of a fluid or air or steam-pressure forcing and discharging apparatus. Whether these jets are derived from the apparatus itself or from a separate source of supply, and whether they are automatic in their operation or depend upon the opening and closing of suitable valves by hand, is

immaterial, provided they aid in the discharge of the material. While we prefer the automatic valve shown, it is evident that we may use any other suitably constructed valve, provided that it is capable of the necessary adjustment and determination both as to the duration of time necessary for supplying the pressure fluid to the ejector and as to the duration of time required for the exhaust air to escape therefrom. It will be apparent that the time required for both operations will vary and will depend upon the nature of the material to be ejected.

Figure 1 shows in section our displacement apparatus specially fitted for the discharge of dry sand, ash and like material, and

Fig. 2 is a corresponding elevation.

In the arrangement shown, *a* is the hopper through which the material is fed, *b* the non-return valve and *c* the closed receptacle into which the sand passes, and *d* the discharge pipe through which the sand is driven out by the pressure of air suitably applied. The compressed air is brought to the closed receiver *c* from the supply pipe *e*. In this instance, the mass of sand within the receptacle is pierced by the pendant air pipes *f*, *f*, *f*, which are connected to the main supply pipe *e*, suitable control valves being fitted at *g*. At *h* is a branch pipe leading from a separate supply to the upper extremity of the receptacle at *j*. This pipe is fitted with a valve *k*. At *l* is an extension of the air pipe *e* through which air is brought to the receptacle at its lower extremity and discharged into the mouth of the delivery pipe *d* through the nozzle *m*. At *n* is a valve by means of which the volume of air passed to *m* may be controlled. At *p* is an orifice which we may use if we wish on the delivery pipe in order to aid the up current which carries the sand and also to serve if we wish as a means of exhaust for the air which is driven out of the closed receptacle by the sand or other material which fills it. When we use this orifice *p* it is evident that as it serves as an exhaust outlet, the air main will be used only to bring compressed air to the ejector in order to displace its contents and never to take the exhaust from it, so that the air valve would never be affected by anything contained in the exhaust air.

The air valve *r* having the usual inlet and exhaust connections is opened and closed at the definite intervals required in order to

open and exhaust the vent aperture and allow air to escape from it as the ejector fills and shuts off the exhaust and admits compressed air to the ejector when the latter is 5 filled in order to drive out the contents thereof. This valve is placed at such a distance from the ejector (and operated apart from it) that it shall not be affected or damaged by the material handled by the 10 ejector. It may be operated through a belt from an electric motor (not shown). The valve shown is of the construction described in the specification of British Patent No. 117,643. Other equivalent forms of valves 15 may be employed for this purpose.

In operation, assuming that the receptacle is full of dry sand, ash, breeze or similar material and that the compressed air is admitted to the receptacle and that the 20 valve *n* is open sufficiently and that the valve *g* is sufficiently open then the compressed air discharged from the pendant pipes *f*, *f*, *f*, will agitate the whole mass of sand which will be downwardly displaced 25 by the pressure of air in the upper extremity of the receptacle, and at the same time the jet of air from the nozzle *m* which is discharging into the mouth of the delivery pipe *d* will drive the sand up into this pipe 30 *i. e.* the result of the combination of these two air forces from above downward and from below upward, will drive the sand, coke breeze or other material up the discharge pipe until the receptacle is entirely 35 emptied. The compressed air then being shut off will allow the receptacle to fill, the exhaust taking place either through an exhaust valve or through the orifice *p* (as in this instance) and the operation will be 40 repeated indefinitely. We may bring in a supply of water or air under pressure either separately or together in suitable proportions to further the object we have in view, as, for instance, at *v* where a jet is used to 45 drive the material from the hopper into the body of the ejector below the non-return valve *b* which this jet of water will keep clear. At *w* is a connection which we may use if it is wished to bring in another current 50 of compressed air into the discharge pipe. It is evident also that we may bring in pressure water or other fluid into such a receptacle through such pipes, *f*, *f* with a water or air jet at *m* when we are dealing 55 with dry or wet sand in combination with an air pressure pipe for displacing the contents of the ejector by the desired pressure of air.

What we claim is:—

60 1. A displacement ejector consisting of a

closed receiver with an inlet for the material to be ejected, air-pipe-connections to the upper part of the receiver, a plurality of air-pipes opening in a downward direction into the body of the receiver near the lower part 65 thereof, a discharge pipe extending into said receiver and opening in a downward direction near the bottom of said receiver, an air pipe extending into the bottom of said receiver and opening upward in the direction 70 of the inlet of the discharge pipe, a source of compressed air, an air-outlet and a power-actuated valve whereby said air-pipes are alternately connected to the source 75 of compressed air and are disconnected therefrom.

2. A displacement ejector consisting of a closed receiver having a rounded bottom and an inlet at its upper part for the material to be ejected, air-pipe-connections to the upper 80 part of the receiver, a concentric series of air pipes opening in a downward direction into the receiver around the lower part thereof, a discharge pipe extending into said receiver and opening in a downward direction 85 in the vertical axis of the receiver near the bottom thereof, an air-pipe extending into the bottom of the receiver and opening upward in the direction of the inlet of the discharge pipe, a source of compressed air, 90 an air outlet and a valve whereby said air-pipes are alternately connected to the source of compressed air and are disconnected therefrom.

3. A displacement ejector consisting of a closed receiver having a rounded bottom and an inlet at its upper part for the material to be ejected, a valve controlling said inlet, air-pipe-connections to the upper part of the receiver, a concentric series of air pipes opening 100 in a downward direction into the receiver around the lower part thereof, a discharge pipe extending downward into said receiver and opening in a downward direction 105 in the vertical axis of the receiver near the bottom thereof, an air-pipe extending into the bottom of the receiver and opening upward in the direction of the inlet of the discharge pipe, a source of compressed air, an air-outlet, a valve whereby such air-pipes 110 are alternately connected to the source of compressed air and disconnected therefrom, and gearing driven continuously for operating said valve.

SAMUEL HENRY ADAMS.
